(57) **CLAIM**

I claim the ornamental design for a hair piece and clip, as shown and described.

DESCRIPTION

FIG. 1 is an upper perspective view of a hair piece and clip; FIG. 2 is a lower perspective view of the design shown in FIG. 1;

FIG. 3 is a front plan view of the design shown in FIG. 1; FIG. 4 is a rear plan view of the design shown in FIG. 1; FIG. 5 is a left side plan view of the design shown in FIG. 1;

FIG. 6 is a right side plan view of the design shown in FIG. 1;

FIG. 7 is a top plan view of the design shown in FIG. 1; FIG. 8 is a bottom plan view of the design shown in FIG. 1; FIG. 9 is an upper perspective view of the clip shown in FIG. 1;

FIG. 10 is a front plan view of the design shown in FIG. 9; FIG. 11 is a rear plan view of the design shown in FIG. 9; FIG. 12 is a left side plan view of the design shown in FIG. 9;

FIG. 13 is a right side plan view of the design shown in FIG. 9;

FIG. 14 is a top plan view of the design shown in FIG. 9; and,

FIG. 15 is a bottom plan view of the design shown in FIG. 9.

The broken lines shown represent unclaimed subject matter and form no part of the claimed design. The shade lines shown represent surface shading and not surface ornamentation, color, or material type. The dot-dashed boundary lines shown do not form part of the claimed design. The bounds of the claimed design are defined with dot-dashed boundary lines when the boundary does not exist in reality in the article embodying the design.
